UNITED STATES PATENT OFFICE.

FRED G. NORMAN, OF DAVENPORT, IOWA.

CAMERA BELLOWS.

Application filed January 20, 1920. Serial No. 352,685.

To all whom it may concern:

Be it known that I, FRED G. NORMAN, a citizen of the United States, residing at Davenport, in the county of Scott, State of Iowa, have invented a new and useful Camera Bellows; and I do hereby declare the following to be a full, clear, and exact description of the invention, such as will enable others skilled in the art to which it appertains to make and use the same.

The invention relates to bellows for cameras, stereoptical machines and other places where a cylindrically shaped bellows is desired.

15 A further object is to provide a substantially cylindrically shaped bellows formed from a heavy piece of paper, leather or other material, said piece of paper being provided with scored lines on opposite sides thereof and out of registration with each other but parallel. One side of the paper being provided with a series of scored lines at right angles to the first mentioned lines and a series of zig zag lines on one face of 20 the paper, said scored lines allowing the paper when its longitudinal edges are secured together to be collapsed so as to form a bellows.

A further object is to form a bellows from 30 a single piece of material, said material being so scored that when the edges thereof are brought together and secured so as to form a cylinder, the cylinder may be collapsed inwardly from its ends so as to form 35 a series of circumferential outwardly and inwardly extending members, each member being formed from a series of sections and the adjacent ends of each section having an overlapping connection so that the sections 40 will not buckle when being forced together.

With the above and other objects in view the invention resides in the combination and arrangement of parts as hereinafter set forth, shown in the drawings, described and 45 claimed, it being understood that changes in the precise embodiment of the invention may be made within the scope of what is claimed without departing from the spirit of the invention.

50 In the drawings:—

Figure 1 is a view showing a sheet of material and series of scorings therein, said view shows the sheet laid out and from the side which becomes the inside of the bellows.

55 Figure 2 is an end view of the cylinder which is formed when the longitudinal edges

of the sheet are brought together and glued or otherwise secured.

Figure 3 is a perspective view of a portion of the bellows showing the formation 60 thereof.

Figure 4 is a sectional view taken on line 4—4 of Figure 1.

Figure 5 is an end view of a portion of the scored sheet before the same is formed 65 into a cylinder.

Referring to the drawings, the numeral 1 designates a sheet of heavy paper, imitation leather or other material from which the bellows is to be formed and 2 the inner 70 face thereof which becomes the inner face of the bellows after the same is formed. The face 3 of the sheet which becomes the outer face of the bellows when said bellows is formed. Face 2 of the sheet is provided 75 with a series of transversely disposed scorings 4, which scorings are in parallel relation to each other and forming bending points when the sheet is folded. By scoring the sheet on its inner face as at 4, it will 80 be seen that when the sheet is formed into a cylinder with its longitudinal edges joined that the portions 5 will extend inwardly at their edges 6, and by providing the outer 85 face 3 with a series of transversely disposed scorings 7 disposed between the scorings 4, the edges 8 of the portions 5 will, when the longitudinal edges of the sheet are secured together and the cylinder so formed crushed inwardly, extend outwardly, thereby forming 90 a bellows. However, it has been found that it is necessary to allow the ends 9 to overlap as the longitudinal edges 10 are brought together and glued, and to accomplish this result the outer face 3 of the sheet 95 is provided with a series of longitudinally disposed scorings 11, which scorings are in parallel relation to each other and to provide the inner face 2 with zig zag scored lines 12 extending longitudinally of the sheet 1 and having their points of angle 13 alternately 100 registering with the scorings 4 and 7 so as to form triangular shaped portions 14. Triangular shaped portions 14, when the cylinder is crushed inwardly, allow of 105 sufficient play as shown at 15, so that the portions 5 will not become buckled as the bellows is moved for shortening or extending its length.

From the above it will be seen that a bellows is provided formed from a single sheet of material, which material is scored on both

sides thereof, so as to allow the inward and outward bending of the sheet when it is crushed inwardly after being formed into a cylinder and that the sheet having been 5 provided with longitudinal scorings on one side and zig zag scorings on the other side thereof, will when the bellows is collapsed allow the bellows to be collapsed or extended as desired. Although the bellows has been 10 set forth for us with camera, stereopticon machines and the like, it is to be understood that the bellows is for general application in any place where a bellows is necessary.

The invention having been set forth what 15 is claimed as new and useful is:—

A polygonal shaped bellows formed from a single sheet of relatively thick fibrous material, said sheet being provided with a plurality of transversely disposed scorings 20 on one side thereof and in parallel relation to each other, a plurality of scorings on the other side of the sheet in parallel relation to each other and to the first mentioned scorings, a plurality of scorings at right 25 angles to the last mentioned scorings, zig

zag scorings on the side of the sheet having the first mentioned scorings, said zig zag scorings having every other angling point in registration with the first mentioned scorings and with the right angled scorings on 30 the other side of the sheet and their intermediate angling points equidistant between the first mentioned scorings and in registration with parallel scorings on the opposite side of the sheet, said angling points being 35 spaced from the right angularly disposed scorings, said scorings when the longitudinal edges of the sheet are brought together and secured allowing the cylinder so formed to be collapsed and the zig zag scorings allowing the bellows so formed to be contracted or extended. 40

In testimony whereof I have signed my name to this specification in the presence of two subscribing witnesses.

FRED G. NORMAN.
